UNITED STATES PATENT OFFICE.

DANIEL A. LOESER, OF SAG HARBOR, NEW YORK.

DESIGN FOR A BACK FOR BRUSHES, &c.

SPECIFICATION forming part of Design No. 26,146, dated October 6, 1896.

Application filed November 30, 1895. Serial No. 570,702. Term of patent 7 years.

To all whom it may concern:

Be it known that I, DANIEL A. LOESER, a subject of the Emperor of Germany, residing at Sag Harbor, in the county of Suffolk and State of New York, have invented and produced a new and original Design for Backs of Brushes, Mirrors, or Similar Articles, of which the following is a specification, reference being had to the accompanying drawing, which shows the back of a brush or mirror having my design applied thereto.

The leading or characteristic feature of my design consists of a series of foliated scrolls located one above the other and decreasing in size from outer end of the brush-back toward that end upon which the handle is formed, at which latter point is formed a leaf-like figure, the stem ends of said foliated scrolls radiating toward an oval-shaped plain surface, into which latter extends leaf-like figures.

Referring to the drawing, A represents a series of foliated scrolls located near the outer edges of the brush or mirror back B and decreasing in size from the upper end of the 25 said back toward the end having the handle C formed thereon, leaving the oval-shaped portion B plain. The converging ends of the scroll terminate in the leaf E, below which are located the foliated scrolls F, the latter 30 being continued in the form of a fanciful border down the sides of the handle C, at the lower end of which latter they meet to form the foliated scrolls G, arranged as shown.

What I claim is—

The design for the back and handle of a brush, mirror or similar article, substantially as shown and described.

DANIEL A. LOESER.
